INVENTOR

JAMES S. JOHNSTON

BY Thomas L. Wilder

ATTORNEY

UNITED STATES PATENT OFFICE.

JAMES S. JOHNSTON, OF UTICA, NEW YORK.

ROLLER.

1,208,567.

Specification of Letters Patent. Patented Dec. 12, 1916.

Application filed March 20, 1914. Serial No. 826,096.

To all whom it may concern:

Be it known that I, JAMES S. JOHNSTON, a citizen of the United States, residing at Utica, in the county of Oneida and State of New York, have invented certain new and useful Improvements in Rollers, of which the following is a specification, reference being had therein to the accompanying drawing.

My invention relates to a roller, and I declare the following to be a full, clear, concise and exact description thereof, sufficient to enable anyone skilled in the art to which it appertains to make and use the same, reference being had to the accompanying drawings, in which like reference characters refer to like parts throughout the specification.

The object of the invention is to provide a simple, efficient roller for use upon typewriters. The roller is of a pneumatic character, whereby to lessen the wear occasioned by the striking of the type against the surface of the platen, as well as to eliminate the noise therefrom. These objects are attained by the mechanism illustrated in the accompanying drawings in which:

Figure 1 is a central section of the roller, showing parts in elevation and the middle portion broken away; Fig. 2 is a fragmentary enlarged section of one end of the roller; Fig. 3 is a central section of a washer employed; Fig. 4 is a plan view of a nut employed.

Referring more particularly to the drawings, the roller comprises a central shaft 1—1— reduced at either end, as at 3 and 4, whereby to form the shoulders 5—5. There is mounted upon the reduced ends 3 and 4, the sleeves 6—6, which have central apertures adapted to project over the enlarged portion of the shaft 1—1—. Annular recesses are formed by the shoulders 7 of the shaft 1—1— with the end walls 8 of the sleeves 6. The end walls 8 are provided with the orifices 9 for the insertion of the reduced portions 3 and 4 of the shaft 1—1—. Upon the sleeves 6 are screw mounted the sleeves 10—10 having the beveled surfaces 11—11 which coöperate with the correspondingly beveled surfaces 12—12 of the washers 13—13 to hold or lock the ends of the platen 14 in assembled position. The washers 13 are each provided with a central aperture 15, so as to be mounted upon the smooth cylindrical surface 16 of the sleeves 10 and are held in assembled position by the octagon nuts 17—17, which are screw mounted

upon the threaded parts 18 of the sleeves 10. The platen 14 is made of a composition comprising rubber and fabric or of any other suitable material that has the desirable resiliency. The sleeves 6 form air tight joints with the shaft 1—1— by means of the packing washers 20 disposed in the annular recesses formed by the shoulders 7 of the shaft 1—1— and the adjacent walls 8 of the sleeves 6.

The chamber 21 formed in the interior of the roller by the platen 14 is filled with air to any desirable pressure by means of an air pump 22 provided with a diaphragm 23 held to the stem 24 by the washers 25—25 and the nuts 26—26. The air pump 22 is located within a cylindrical recess 27 formed in the shaft 1—1—. The stem 24 projects through an aperture 28 in the plug 29 screwed to the interior of the recess 27 and having key holes 30 for its assembling. There is a handle 31 for the suitable manipulation of the pump 22. The recess 27 terminates in a recess 33 constructed at right angles to the recess 27 and opening into the interior of the chamber 21. The opening of the recess 33 is normally closed by the member 34 secured to the outer end of the spring 35, which is fastened at 36 to the shaft 1.

On either end, 3 and 4, of the shaft 1—1—, there is mounted the members 37—37, whose outer surfaces are corrugated. The members 37 are held upon the ends, 3 and 4 of the shaft 1—1— by the set screws 38, that pass through the threaded apertures in the sleeves 39 of the members 37, and thereby engage the surfaces of the ends 3 and 4 of the shaft 1—1—. The members 37 are provided with a concave portion 40 for the purpose of ornamentation, as well as to permit, at the end 3, of the convenient grasping of the handle 31 of the pump 22.

The assembling of the roller is effected by mounting the packing washers 20 and the sleeves 6 and 10 upon the ends 3 and 4 of the shaft 1—1— and engaging the ends of the platen 14 between the beveled surfaces 11 and 12 of the sleeves 10 and washers 13, respectively. These parts are locked in position by the octagon nuts 17. The platen 14 is drawn tight in a longitudinal manner, whereby to take up any slack by turning in a given direction, the sleeves 6, which are provided with nut heads 41 for the purpose, and thereby causing the sleeves 10 to travel longitudinally outward from

the center of the chamber 21, or in opposite directions from each other. The tightening of the platen 14 also effects a pressure of the end walls 8 upon the packing washers 20, whereby to not only make an air tight joint at that part but also to hold the sleeves 6 tightly against the shaft —1—, so that the same and the other parts mounted thereon together with the platen 14 will revolve 10 with the shaft —1—. As thus assembled the roller is mounted in its proper place in a typewriting machine or other similar device.

The chamber 21 of the roller can be filled 15 with air and kept filled with air to any desired degree by working occasionally the air pump 22, which sucks in the air through the orifice 42 in the plug 29 and compresses it into the chamber 21 by way of the recesses 27 and 33. The member 34 will yield, as shown in dotted lines in Fig. 2, upon each compression stroke of the pump to admit the air to the chamber 21 and will close immediately thereafter because of the normal 25 tendency of the spring 35. The members 37 permit the roller to be turned independently of the actuating mechanism of the typewriter.

Having thus described my invention what 30 I claim as new and desire to secure by Letters Patent is:

1. In a roller, a platen, compressed air for giving said platen resiliency, means for forcing air into said roller and mechanical 35 means for drawing said platen in a longitudinal direction, whereby to tighten the same.

2. In a roller, a platen, a chamber in said roller, means for holding air under pressure within said chamber, means for increasing said pressure to any desired degree and sleeves for drawing said platen in a longitudinal direction, whereby to tighten the same. 40

3. In a roller, a platen, washers having beveled surfaces for securing the ends of said platen in assembled position, compressed air for holding the surface of said platen in yielding position, means for keeping said compressed air in normal condition 50 and sleeves for drawing said platen in a longitudinal direction, whereby to tighten the same. 45

4. In a roller, a platen, a chamber in said roller, means for holding air under pressure 55 within said chamber, a pump for keeping said pressure up to normal pressure and sleeves provided with nut heads for drawing said platen in a longitudinal direction, whereby to tighten the same. 60

5. In a roller, a platen, a sleeve and a washer for holding each end of said platen in assembled position, a second sleeve for tightening said platen, a chamber within said roller, and means for forcing air into 65 said chamber, whereby to form a pneumatic cushion for said platen.

In testimony whereof I have affixed my signature in the presence of two witnesses.

JAMES S. JOHNSTON.
